[57] ABSTRACT

Two embodiments of an apparatus for preparing and wrapping stripped ends of wire especially on electrical terminals for interconnecting the terminals are disclosed. An X, Y locator is used to shift and accurately position the wire wrapping head of the apparatus. The head includes a wrapping tool to which wire of an indeterminate length is fed, cut, stripped and loaded in a unique, fully automatic manner at the first end, and then the procedure is repeated at the second end. Additional wires are automatically connected in accordance with data supplied to the X, Y locator. Gripper means positively hold the wire adjacent the

tool and the tool is advanced and retracted from each terminal on a sliding carriage. The wrapping tool includes a non-rotatable bit element having a slanted, open notch on the side for efficient side loading and a rotatable elongated concentric sleeve. The sleeve has a bisected slot for loading of the stripped end in a closed groove portion thereof and through an open groove portion and the notch. The loading operation is performed by relative shifting of the sleeve and only after the end has been cut and stripped to prevent fracture of the wire. A feed tube shifts the wire to a position between a movable door and backup assembly that carries blades and forms the stripping and cutting means and then through a cam-shaped clamp means to positively control the end of the wire; the clamp being made more effective upon movement of the wire in a second direction and into a U-loop that is caught by catch means on the side of the cam. An anti-backforce mechanism is provided by a second sliding carriage with a biasing means connected between the same and the base member that is carried by the locator means. This mechanism is operative at least during advancement of the tool to the terminals to prevent damage to terminals should misalignment occur. Control means between the sliding support of the loading means and the support for the main frame or sliding carriage assures proper loading and full advancement and retraction of the tool. An air turbine motor preferably rotates only the sleeve for the wrapping operation and indexing of the sleeve is performed while single direction rotation is maintained. Holder means guides the second end of the wire for proper reception by the gripper means. All of the above structure is present in both embodiments of the invention, it being understood that the difference lies in specific structural details, as will appear below.

WIRE HANDLING AND MANIPULATING APPARATUS

The present invention relates generally to the art of handling and manipulating wire to make electrical interconnections, and more particularly, to an improved apparatus for automatically cutting and stripping in sequence two ends of a wire from a supply of indeterminate length and wrapping or affixing the prepared ends to separate electrical terminals.

BACKGROUND OF THE INVENTION

Solderless wrapped connections on "airline" type wiring between electrical terminals have become standard for wiring computers, television, communications equipment and similar electronic gear. In a typical manufacturing process where two electrical terminals are to be connected, a length of wire is pre-measured and pre-stripped at both ends and one end of the wire is inserted at a time into a special tool, the tool is placed on the terminal post and the bare wire is coiled tightly around the post by rotary action of the tool. This wrapping process is repeated for the second end of the wire after extending the wire to the second terminal thereby creating an electrical interconnection. Wrapped connections have demonstrable advantages, such as: (1) shorter elapsed time for making a connection; (2) no additional parts required; (3) high shearing force at the corners of the terminal to assure clean metal-to-metal contact and sealing of the contact area from ambient conditions; (4) greater mechanical attaching stability on the terminal so that assembly and handling operations and vibrations do not cause loosening of the wire; and (5) wider clearance between the adjacent terminals so that a larger number of connections per unit area can be realized.

As the technology of computers has increased and integrated circuits have brought about a reduction in the hardware size, the pressure has increased considerably for making the terminal boards that support the circuits smaller. As mentioned above, the wrapped connection is best suited of all of the known ways of making a high quality connection, but the smaller spacing and the greater number of wires flying over the terminal board has made it increasingly difficult to economically provide the necessary interconnections.

To alleviate the problem, machines have been introduced in recent years that are known in the art as semi-automatic wiring machines. These machines are in reality merely position locators that sequentially identify for the wire wrapping technician the terminals that are to be interconnected. Such a machine typically provides a mounting for the terminal board and adjacent the board an X, Y locator with pointer which moves in response to data from a pre-coded punched or magnetic tape. When the end of a pointer stops, it is in alignment with the terminal that is to be wrapped and the operator then manually inserts the stripped end of the wire into the hand-held tool, engages the terminal with the tool and activates the tool to wrap the wire. The locator is then programmed upon receiving a signal from the operator to go to the next terminal to be connected and the manual wrapping process is repeated. These machines have in-

creased the production dramatically to approximately 500 terminations per hour, and thus are in widespread use, especially among small to medium size computer manufacturers and users. However, as the uses and complexity of computers continues to accelerate, still more economical and mistake-proof means for performing the wire wrap operation, especially for the small and medium size users is needed.

10 To our knowledge, there has not been any successful solution to the problem of fully automating the wire wrapping procedure for the small to medium size operations that have in the past used the semi-automatic wiring machine. On the other hand, for 15 the large scale user and equipment manufacturers, machines have been proposed to fully automate the wire wrapping procedure. Representative of the efforts in this area are the machines disclosed in the patent to Madden 2,696,656, issued December 14, 20 1954, and the patent to Bos et al. 3,103,735, issued September 17, 1963.

In the Madden patent, the principle of automatic wire feeding and wrapping is taught; however, as can be seen from the disclosure, the tool is relatively 25 complex, and most importantly, it is incapable of making wrapped connections on closely spaced terminal posts found in a computer installation. The machine represented by the Bos et al patent is even 30 more complex and expensive, requires a large area that makes it unsuitable for operations where floor space is at a premium, has proven to be incapable of effective monitoring and control by an operator, and is even unsafe in an emergency. Furthermore, the 35 machine requires two separate wrapping heads for making the two wrapped connections of one wire and a highly complex logic system for determining the length of the wire and the proper spaced location of the two heads. Thus, a machine made in accordance 40 with the teaching of Bos et al., or Madden, not only limits the market to which automatic wire wrapping machines can be supplied, i.e., to the few relatively large users and hardware manufacturers, but also these machines have certain inherent shortcomings in 45 terms of efficiency of operation.

OBJECTIVES OF THE INVENTION

Accordingly, it is an object of the present invention 50 to provide a simplified and low cost apparatus for automatically performing the wire wrapping operation on computer terminal boards or the like.

It is another object of the present invention to 55 provide a machine that is not only low cost and fully automatic, but which also has the capability of working on closely spaced terminals and that may be monitored and controlled in a safe manner by an operator in an emergency situation.

It is still another object of the present invention 60 to provide an improved wire wrapping apparatus, and subcombinations thereof, that is specially designed for use in conjunction with a conventional position locator, thereby giving many small and medium size users capability of conversion from semi-automatic 65 to automatic wire wrapping.

It is still another object of the present invention to provide a wire wrapping head of simplified and lightweight design and with superior mechanical

features to handle and manipulate the wire while maintaining the same under positive control at all times.

BRIEF DESCRIPTION OF THE INVENTION

A wire wrapping apparatus and subcombinations thereof constructed in accordance with the principles of the present invention comprises a rotary wrapping tool for wrapping the stripped and cut ends of a wire on spaced terminals to form an interconnection of high integrity, means for catching and loading the wire on the tool, stripping and cutting means for forming the connector ends, and means for advancing and retracting the tool along the Z axis of the tool toward the terminal in a rapid, but delicate manner. In the overall combination invention, these components, which collectively form a wire wrapping head, are coupled with locator means for traversing the tool to new X, Y locations for each new first and second end wrapping.

In accordance with one specific aspect of the present invention, a gripper means is provided adjacent the tool to positively hold the wire while stripping the ends and loading into the tool. And, a lower clamp is provided adjacent the cutting means to further provide additional positive holding of the wire through a U-shaped loop of wire that assures continued operation without interruption. The entire handling and manipulation means for the wire with the positive control is furthermore advantageously designed so that a single tool with minimal frontal area is operative to position and wrap both ends of the wire.

The wrapping tool is in and of itself important to the invention in that it allows convenient side loading of the prepared end. A sleeve that is concentric with the bit element is mounted for relative rotation therewith. The sleeve is provided with a longitudinally extending slot bisected by the bit element to form an open groove and a closed groove contiguous with the bit element. Upon relative axial shifting between the sleeve and the bit element the wire is loaded into the closed groove by passing through the open groove and the notch. The wire is loaded in the tool by means separate from the cutting and stripping means so that fracture of the wire due to excessive tension is avoided.

The stripping and cutting subcombination includes a movable door and backup assembly that mounts the opposed stripping blades and the cutter blade for simultaneous operative movement. The assembly is mounted on slide means that moves toward the end of the wire only after the cutting and the score for the stripped insulation has been completed.

The lower clamp for positive control is positioned below the cutting blade and includes, more particularly, a pivotal cam element having an operative gripping surface and an opposed jaw forming a nip to trap the wire. The cam element is pivoted to open to receive the wire automatically as the same is pulled in the first direction therethrough, and catch means on the side of the cam element actually increases the clamping action when the wire is pulled in the opposite or second direction. In one embodiment a V-shaped catch is employed on the side of the cam element to positively trap the wire. The U-shaped loop

formed by the cam element in either embodiment plays an important role in assuring positive control of the wire at all times, as mentioned above.

The feeding means subcombination includes a feed tube carrying the wire that is mounted substantially normal to the tool rather than in the same direction thereof so that the tube does not require advancement with the tool to the terminal board where interference with the terminals could occur, as in prior art machines, such as shown in the Madden patent. Means is provided for shifting the feed tube to provide a new length of wire through the stripping and cutting means and for engagement with the lower clamp. The tube is mounted for pivotal action to permit glancing movement past the gripper means that serves to catch the wire and hold the same in position for receipt in the side loading notch of the bit element. In one embodiment, the gripper means plays an important role of further assuring continued positive holding of the wire so that the same does not escape during the critical loading operation in the tool. The gripper in this embodiment includes two elongated jaws, one stationary and one movable, that can move forward with the sleeve on the loading operation and, if desired, for the wire wrapping operation. The ends of the gripper jaws are narrow so as to be easily accommodated between adjacent rows of the terminal posts on the terminal board and serve to tuck in previously attached wires. However, since the entire wire end is held firmly in the closed groove of the tool after loading, the gripper means need not be advanced at all or advanced all the way to the terminal board for a successful wrapping operation. In fact, in a second embodiment illustrated, the gripper means remains stationary and a separate pusher means serves to carry forward the wire adjacent the wrapped end and tuck the same between the terminals. The stripped wire end in both embodiments is advantageously carried totally within the tool after loading so that it does not stick out the side of the tool where it could fly around out of control during the tool rotation.

A motor means, such as a pneumatic cylinder, is connected to a sliding support in order to perform the loading operation through relative movement of the sleeve and the bit element. This motor is carried by a mounting assembly to provide a reaction point for movement of said support, and the main frame of the head forms a first sliding carriage on the assembly also responsive to said motor means. With this configuration in the first embodiment, the motor means thus serves the function of not only loading the wire in the tool, but also of bringing the tool by movement of the main frame into engagement with terminals. In the second embodiment, a separate motor may be employed for the latter function. The mounting assembly forms a second sliding carriage on a base member (that is in turn carried by the X, Y locator means), thereby providing an additional relative motion interface. Biasing means is connected in accordance with the invention between the mounting assembly and the base member to provide an anti-backforce mechanism which automatically produces the proper wrap tightness on the terminal post. The additional movement and biasing interface also serves to limit the forward force of the tool to

prevent bending of a misaligned terminal. When a bent terminal pin or post is encountered, the operator, who may have responsibility for several automatic wire wrapping machines designed in accordance with the present invention, simply manually retracts the wire wrapping head against the force of the spring, straightens the terminal and releases the head, whereupon the post is properly engaged by the tool and the wrapping proceeds without further interruption or down-time of the machine.

As an added feature in the second embodiment illustrated in this application, the biasing means may be mounted for retraction from second carriage engagement as the wrapping operation is initiated. In this instance, only the friction between the parts controls the backforce for wrapping, which condition is preferred under certain circumstances, such as where relatively light gauge wire is used.

An operational feature in the first embodiment includes the use of a novel latch means and differential friction between the sliding support and the mounting assembly to assure full and proper sequential advancement and retraction of all parts. Of course, in the second embodiment, where a separate cylinder is employed, no such latch means is required. The sleeve for performing the wrapping of the wire is indexed by a rotating arm engaging a stop means during the retraction movement of the tool. The indexing can in accordance with the invention take place while the sleeve continues to rotate in the same direction as the wrapping. The indexing is performed and maintained by a secondary and lower pressure on the air turbine drive motor. If the friction in the tool is insufficient to hold the tool against rotation after the wire is loaded, the lower pressure may be terminated as the tool starts to move forward so that the proper position is held until wrapping is initiated. A holder means captures the wire when the head is moved to the second location in order to position the wire for catching by the gripper means to assure proper formation of the second stripped end. In the first embodiment, control of the wire during the stripping and cutting operation is further assured by using a single motor that closes the door prior to any movement of the slide means and by providing angled projections on the stripping blades that form intersecting V's to enclose the wire prior to the cutoff by the knife. Separate motors for the door and the slide means are contemplated in the second embodiment.

Within certain broader aspects of the present invention, it is contemplated that the wire handling and manipulating subcombinations of both embodiments have utility for making electrical interconnections where the end of the wire is affixed to the terminal without wrapping such as by a chemical bonding process. Of course, the side loading wire wrapping tool subcombination can be used in other semi-automatic or automatic wire wrapping environments. The pivotal clamp that is self-loading and capable of providing increased holding force when a wire loaded therein is pulled in a second direction can be utilized in analogous manufacturing processes where control of a piece of wire is necessary. One such application would be in the making of wire harnesses on a jig board with the pivotal clamps serving to locate the ends of the wires for convenient attach-

ment of whatever connector is desired.

Still other objects and advantages of the present invention will become readily apparent to those skilled in this art from the following detailed description, 5 wherein we have shown and described only the two preferred embodiments of the invention, simply by way of illustration of the best modes contemplated by us of carrying out our invention. The first embodiment illustrated is preferred for its simplicity of structure, 10 and thus lower initial cost, and for its advantages in terms of combining functions for rapid and assured sequential operation. The second embodiment is preferred for its reliability of operation at the present time. This reliability results mainly from separate 15 mechanical mechanisms and operators for performing each of the several functions in the wrapping operation, as well as different designs and configurations of the parts and elements. As will be realized, the invention is capable of still other and different embodiments, and its several details are capable of modification in various obvious respects, all without departing from the invention. Accordingly, the drawings (FIGS. 1-14, first embodiment, and FIGS. 20 15-17, second embodiment), and the description of 25 the two embodiments, are to be regarded as illustrative in nature, and not as restrictive. Unless otherwise clear from the language therein, the invention is to be interpreted in all instances as broad enough 30 to cover both embodiments illustrated, as well as all equivalent embodiments.

BRIEF DESCRIPTION OF THE DRAWINGS

35 FIG. 1 is an overall perspective view of a wire wrap head and base assembly constructed in accordance with the teachings of the present invention;

FIG. 2 is a perspective view of the wire wrap head 40 and base assembly of the invention showing the side opposite of that shown in FIG. 1;

FIG. 3 is a section view taken through the wire wrap head of FIGS. 1 and 2 showing portions of the wire feeding, catching and loading, and stripping 45 and cutting mechanisms of the present invention;

FIG. 3A is a showing like that of FIG. 3 but with the parts in a different sequence step;

FIG. 4 is a plan view of a wire wrapping head 50 mounted on an X, Y locator forming the combination inventive concept of the present invention;

FIG. 5 is a schematic diagram of the control system and actuators of the invention;

FIG. 6 is a side view of a portion of the wire wrapping head;

55 FIG. 7 is a top plan view of the head constructed in accordance with the principles of the present invention, and showing the gripper means and its relationship with the wrapping tool, and the indexing means, in more detail;

FIG. 7A is a top plan view like FIG. 7 showing the indexing means at a different sequence step;

FIGS. 8, 9-9A, and 10-10A show in sequence the catching and loading operations of the apparatus of the present invention;

65 FIG. 11 is an enlarged detail and cross-sectional view of the wire wrapping tool with a stripped wire in a fully loaded position in readiness to perform a modified wrap on a terminal post;

FIGS. 12 and 13 show the supporting base assembly including the anti-backforce arrangement, with positioning of the latch means in sequence for loading and then for forward advancing movement for wrapping; and

FIG. 14 is a final sequence showing positioning and holding of the wire in readiness for forming the second stripped end.

FIGS. 1-14 thus in composite, show the first embodiment of the invention, and the second embodiment is shown in FIGS. 15-17, described below.

FIG. 15 is a top plan view of the wire wrap head and base assembly of the second embodiment of the invention:

FIG. 15a is a section view taken along line 15A-15A of FIG. 15 showing the clamp element that forms the U-shaped loop to control the free end of the wire:

FIG. 16 is a transverse section view taken through the assembly of FIG. 15 along line 16-16 showing portions of the wire feeding, catching and loading, and stripping and cutting mechanisms of the present invention;

FIG. 17 is a longitudinal side section view taken through the assembly of FIG. 15 along line 17-17 showing substantially all the remaining parts of the basic structure of the second embodiment; and

FIG. 18 is a section view like FIG. 17 showing the parts in a different position with the wire end stripped and the holder pin withdrawn.

DETAILED DESCRIPTION OF THE PREFERRED EMBODIMENT

With reference now to FIGS. 1-3 of the drawings, there is disclosed therein a wire wrapping head 10 embodying the several features of the first embodiment of the present invention. In general terms, the wire wrapping head 10 comprises a main frame 11 that houses a wire catching and loading means, generally designated by the reference numeral 12, stripping and cutting means 13 and head advancing and retracting means 14. A rotary wire wrapping tool 15 is provided on a sliding support 15a on the upper portion of the head 10 in juxtaposition with the catching and loading means 12. As best shown in FIG. 3, a wire W may be fed from a suitable location adjacent the head 10 from reel R containing wire of indeterminate length. The wire W is fed through a bodily movable feed tube 16 extending normal to the tool 15, said tube 16 having an outlet orifice 17 positioned just above the end of said tool 15. The wire W is adapted when extending downwardly past the tool 15 (see FIG. 1, for example) to be in cross engagement therewith, and is held in this position by a pair of opposed gripper jaws 18, 19 forming an important part of the catching and loading means 12.

The feed tube 16 is carried by a support block 20 pivotally mounted on the piston rod 21 of a suitable air cylinder 22. The piston may be double acting or spring biased to raise the tube 16 to its uppermost position, as shown in FIGS. 3 and 3A. Upon actuation of the cylinder 22, the feed tube is pushed down to the dotted line position shown in FIG. 3. This downward movement when initializing wire portion 65 W₁ of the wire is held up serves to feed an initial length of wire into the lowered dotted line position

shown. When the wire W is thus positioned it extends through the stripping and cutting mechanism 13 and an initial cut is made by the knife, as will be seen below. This positioning and cutting of the wire W is known as the "initializing" process and is the only step required to completely set the head 10 in readiness for operation and needs to be performed only when the roll R of wire W is to be replenished.

The stripping and cutting means 13 includes a pivotal door 25, on the top of which is mounted a stripping blade 26 and on the bottom of which is mounted a knife or cutting blade 27 (see FIG. 1). The door 25 is supported on a backup member and slide means 28 that carries an opposed stripping blade 29 and an opposing slot for the knife 27. The blades 26, 29 have dual projections forming opposed V's serving to locate and capture the wire W as it moves through the mechanism, as shown by the dotted lines in FIG. 3. These projections are designated by reference numeral 26a in FIG. 3.

On the lower portion of the slide means 28 there is mounted a lower cam-shaped clamp 30, that is pivotally mounted and spring biased in the counter-clockwise direction, as viewed in FIG. 1. This clamp catches and traps the wire W as the outlet end 17 of the feed tube 16 moves down to its lowermost position and through the nip. The clamp 30 holds that portion of the wire that is to become the U-shaped control loop, as will be apparent shortly.

The door 25 is spring biased to open to the position shown in FIGS. 1 and 2. A lower corner of the door 25 is provided with a cam surface 35 that is operative to be engaged by a pivotal actuating cam 36 mounted on the slide means 28. The upper face of the cam 36 is positioned for engagement by a downwardly moving piston rod 37 of a second pneumatic cylinder 38. Slide means 28 is constantly urged in the upper direction by compression spring 39. It will be realized that the single cylinder 38 is operative to first close the pivotal door 25 through the action of the cam 36, and thereafter (when the cam 36 can pivot no farther because the door has reached its fully closed position) to start the slide means 28 travelling in the downward direction. It is important to note that the opposed projections 16a have captured the wire. The opposing sharpened portions with the V's score the insulation in a line around the wire W, and at a point below, the knife 27 has cut the wire, thus forming the end thereof.

As the slide means 28 moves toward its final downward position, the initial operative end is held in the lower clamp 30. Since the wire is freely movable through the feed tube 16, a brief retro movement of the wire W may take place and is taken up by any suitable slack means (not shown). It is also understood that the roll R is mounted on any suitable arbor or cradle and may be regulated by suitable brake means (not shown) to prevent overrunning. When the slide means 28 has reached its final lowered position (see, for example, FIG. 9) the initializing wire portion W₁ is removed and may be discarded whereupon the machine is ready to commence making wrapped interconnections between terminals.

The head 10, whose major functions have thus far been broadly described, is mounted on a suitable locator means, generally designated by the reference numeral 40 in FIG. 4. The locator may be merely a

semi-automatic wiring machine presently sold on the commercial market by several companies, such as Standard Logic, Inc. of Santa Ana, California 92707. The specific locator shown in the present preferred embodiment can be readily related to the Standard Logic, Model No. WWM-300 that employs crossed lead screws 41, 42 on slideable supports carried by a rectangular frame 43. The usual pointer of the locator 40 has been converted to a travelling slide carrier 44.

The wire wrapping head 10 has, as is shown in FIGS. 1 and 2, a base assembly 45 and this assembly is mounted directly to a base plate 46 carried by the locator slide carrier 44. With this mounting, it is clear that the head 10 is capable of movement in the X direction, as denoted by the double ended arrow a_1 , and in the Y direction, as indicated by the double ended arrow a_2 , in order to be positioned over any selected terminal t on terminal board B. As is well known in the art, motors 47, 48 activate the screws 41, 42, respectively in accordance with control logic means 49 that may be responsive to either punch tape, magnetic record or otherwise controlled.

A significant aspect of the inventive concept of the present invention is to provide a wire wrapping head 10 that is of a simple and lightweight design so as to be adapted to be carried on a conventional X, Y locator, such as the Standard Logic locator 40 shown. This successful design and novel combination of mechanisms of this first embodiment of the present invention gives results not heretofore obtained. In essence, a low cost, and yet fully automatic and dependable wire wrapping apparatus has been realized. Small and medium size firms can now afford automatic wire wrapping machines, and semi-automatic machines may be easily converted. It should however be clearly understood that the specific type of X, Y locator is of no particular patentable moment, and that therefore, the wire wrapping head 10 of the present invention can be used with any number of others, such as the type of locating device shown in the Bos et al Patent 3,103,735, cited above, without departing from the principles of the invention.

An important factor in designing a wire wrapping head 10 capable of being successfully carried and positioned on the X, Y locator 40 in both of the embodiments of the invention was found to be the simplicity of construction and design of the movable parts and the actuators for controlling the same. In addition to the pneumatic cylinders 22 and 38 described above, in the specific first embodiment there is required only two additional linear actuators; a pneumatic cylinder 50 that is operative to close the gripper jaws 18, 19 and a main cylinder 51 for loading the wire in the tool 15 and thereafter advancing the main frame 11 to bring the tool 15 in engagement with the terminals t . A single air turbine motor 52 is provided to drive the wrapping tool 15 and is carried by the sliding support 15a. A general view of the placement of these motors may be seen in FIGS. 1 and 2 of the drawings.

In FIG. 5, a complete schematic of the operating controls for these actuators has been illustrated. Here, it can be seen that each of the pneumatic cylinders 22, 38, 50 and 51 may be connected through control lines to a simple fluidic control circuit 55 for actuation in proper sequence. Although a fluidic control system (that is, utilizing pure fluid elements

and switches), is desired for proper actuation of the cylinders because of its lightweightness, simplicity of design and low cost, it is obvious that electronic controls, including electrically operated switches and valves, could also be utilized to operate the components in proper sequence. Since the particular configuration of the control circuit 55 is of no import to the present invention, no further showing is deemed necessary. The typical system, such as shown in the Bos et al Patent 3,103,735, could be easily adapted by one skilled in the art in order to practice the present invention.

The control circuit 55 also may be provided with an additional air pressure line 56 that may be connected to a suitable inlet 57 (see FIG. 2) on the back of the pivotal door 25. A passageway in the door opens on the interior side, and when a pulse of air is provided through the line 56, the stripped length of insulation left by the previous stripping cycle will be dislodged and blown free.

The control circuit 55 may be provided with the necessary compressed air from a conventional compressor 60 through a high pressure trunk passageway 61. The motor 52 is provided with its high pressure driving air through a servo valve 62 operated by said control circuit 55 and a shuttle valve 63. The shuttle valve 63 also has constant low pressure supplied through input passageway 64. As will be evident, when the valve 62 is deactivated (not providing high pressure air via the passage 61), the low pressure air 64 shifts the shuttle ball 65 to the position shown, so that the turbine 52 is driven constantly forward in a standby condition at low power. When the valve 62 is opened by command from the circuit 55, the high pressure air biases the ball 65 to the right in FIG. 5, and the turbine is immediately operated on high pressure. The high pressure mode is utilized for the power or wrapping cycle and the low pressure mode is utilized for indexing as will be further explained. Typically, the high pressure air may be supplied at 80 pounds per square inch and the low pressure air regulated to approximately 5 pounds per square inch.

As shown in FIG. 6, the air turbine 52 drives the tool 15 through suitable gears 70, 71. Tool 15 is supported by suitable bearings in the sliding support 15a and may be easily removed for replacement, as is necessary from time to time due to wear.

As shown in FIG. 7, the gripper jaws 18, 19 are elongated and extend substantially parallel with the tool 15. The jaw 19 is slightly offset to the left (in this figure), so that the wire adjacent the stripped end held by gripper avoids interfering with the adjacent terminal when the tool 15 has moved to the full "in" position (FIG. 11). The movable jaw 18 is carried by the stationary jaw 19 by suitable parallel links 72, 73, thus providing for parallelogram type movement of said jaw 18. This movement is generated by an operator cam 74 mounted on the movable jaw 18 and positioned for engagement by the push rod 75 of the actuator cylinder 50. The parallelogram type linkage assures a strong sidewise component to make certain of secure gripping action of the wire at the operative portions of the jaw 18, 19 adjacent the ends or tips (see FIG. 3). The slanted engaging surface 76 further assures a positive sidewise gripping force and secure locking of the jaws 18, 19 together under continued actuator force. A return spring 77 is provided to open

the jaws 18, 19 at the appropriate time in the cycle when the cylinder is deactivated.

To perform the rotary indexing function on the tool 15, the upper or driven gear 71 has a radially extending indexing arm 80 engaging a stop finger 81 when the sliding support 15a is in the retracted position (FIG. 7). The arm 80 moves free of engagement when the support 15a has advanced beyond the extent of the stop (FIG. 7A). With reference back to FIG. 5, the valve 62 is opened only after the stop 81 has been disengaged and full power is applied to the tool through the shuttle valve 63 for the wrapping operation. When the support 15a is again retracted, the low pressure is again applied and the stop 81 is engaged automatically thereby stopping and then retaining the tool in the proper orientation for the next loading operation. With this arrangement, it will be realized that indexing is simply yet positively accomplished at just the right time during the cycle and without the need for troublesome reversing of the tool as required in prior art arrangements.

After the initializing operation, that has been explained in conjunction with FIG. 3 takes place, the feeding cylinder 22 is presently to be deactivated so as to raise the feed tube 16 to its uppermost position, as best shown in FIG. 8. It will be remembered that at this point the grippers 18, 19 are open in anticipation of receiving the wire W and also the stripping and cutting door 25 is open for the positioning of the wire that is to occur. It should also be noted with respect to the showing in FIG. 8 that the pivoting action of the feed tube 16 allows the outlet end 17 to glance past the stationary gripper 19 to prevent damage to the parts and so that in the final catching position the wire W is held firmly against said gripper 19 and the tool 15. The pivoting action also assures favorable glancing action through the lower clamp 30.

The value of the lower clamp 30 can be further identified in the showing of FIG. 8. Here, the wire terminal portion W₂ has been formed by the initializing cutoff and by movement of the feed tube 16 in the opposite or the second direction a U-shaped loop has been formed about a V-shaped catch formed by a pin 85 extending from the side of the clamp 30. The outer insulation of the wire is wedged and caught in the V. This assures that the clamp 30 is tended to be further rotated in the clockwise direction. This action, in turn, tends to rotate the cam 30 so as to assure that inner gripping surface 86 is clamped even harder against the wire terminal portion W₂ held against opposed jaw member 87, and thus, positive control of the wire terminal portion W₂ is advantageously gained. This U-shaped loop is important to the operation of the present invention in that it alleviates the problem of the wire end possibly flying loose, as can occur in other clamping arrangements.

Reverting momentarily to FIG. 3, it will be remembered that the tool 15 is positioned directly below the outlet orifice 17 of the feed tube 16. At the upper end of the stroke, a stop 90 is positioned to hit the inlet end of the tube 16 and thus pivot the outlet end 17 higher than would normally occur and thereby slightly increase the stroke. Also, the stop 90 can serve as a means for locking the end 17 of the tube 16 in the exact position to insure catching of the wire W on the tool 15. Similarly, when the feed tube 16 reaches its dotted line position below, stop 91 serves

to pivot the same to increase the stroke and to lock the tube 16 in position. In this manner, the precise feeding of the wire W and the locking in the upper and lower positions is ensured.

The next step of the sequence is shown in FIG. 9 and 9A. Here the gripper jaws 18, 19 have captured and are holding the wire just below the outlet end 17 of the feed tube 16. Immediately thereafter, the cutter and stripper cylinder 38 is activated to first close the door 25 and trap the wire between the projections 26a, on the blades 26, 29, score the wire by the interaction of said stripping blades 26, 29, and cut the wire by the knife 27 spaced therefrom. When the cam 36 is completely rotated (FIG. 3A), the slide means 28 carrying the stripping and cutting means 13 and the lower clamp 30 is moved downwardly. Thus, a first stripped end E₁ has now been completely formed in readiness for wrapping (see FIG. 9).

At this point, a more detailed look at the structure 20 of the tool 15 should be taken. The bit element 90 has an aperture 91 formed in its free end for receipt of the terminal t to be wrapped. The free end projects outwardly beyond the main frame 11 at all times so as to be capable of engaging said terminals t without interference. The bit element is held stationary, both 25 in the rotary and axial sense, by a locking screw 92 engaging the same at the rear of the main frame 11, as shown in FIG. 1. A notch 93 is formed in the side of the stationary bit element 90 for side loading of the 30 wire W, as shown by the prepared end E₁ in FIG. 9A. The side loading feature is particularly advantageous in automatic wrapping since this leaves the face of the main frame 11 free from structure that would interfere with the movement of the tool to the terminal board B. The tips of the gripper jaws 18, 19 when moved to the full forward position with the tool 15 fit 35 between the adjacent space between horizontal rows of terminals t, and due to the offset of the stationary jaw 19 conflict with the adjacent terminal t in the vertical direction is also avoided. Wires already in 40 position from previous operations are tucked in between the terminals t by the tips for a neater finished product.

The tool 15 further comprises a rotatable and axially 45 movable sleeve 95 mounted concentrically on the bit element 90. The sleeve 95 is the part that is directly attached to the gear 71 and is thus driven thereby. The sleeve is mounted in suitable bearings in the sliding 50 support 15a and may be held in position by suitable expandable clips to allow removal as necessary when the tool has become worn. The operative face 96 of the tool engages the wire as it is being wrapped thereby causing the greatest area of wear and necessitating the periodic replacement. The face 96 is 55 provided with projecting camming area 97 that serves to push each wrap of the wire snug against the previous wrap as the sleeve rotates.

The sleeve 95 has a longitudinal slot opening 60 adjacent the bottom, as orientated in FIG. 9A. The slot is bisected by the stationary bit element 90, and thereby forms a closed groove 98 and an open groove 99 contiguous with the bit element 90 (see FIG. 11). The upper groove has, of course, less radial extent and is designed to hold the stripped end of the wire W when the end is ready for wrapping. The lower groove 99 is designed to simply allow free passage of the stripped end E₁ as it is drawn in by the notch 93

during the loading operation. The sides of the notch 93 are sloped to further assure non-binding passage of the wire W in the tool 15 during loading. Thus, as the sleeve 95 moves forward by movement of the sliding support 15a (FIG. 1), it will be realized that the point 100 of the wire end E₁ is engaged by the upper bridge portion of the sleeve 95 at the face 96. The wire end E₁ is thus bent at substantially 90°, and turns into the groove 98.

FIG. 10 shows the sleeve 95 moved forwardly to a partially loaded position, and FIG. 10A shows the tool 15 in close-up detail of this stage, similar to the showing in FIG. 9A. As the sleeve 95 continues to move relative to the bit element 90 the finished or stripped wire end E₁ is pulled by and through the notch 93 and continues to be extended back through the groove 99 and aligned in the closed groove 98 parallel to the tool axis.

The final position of the end E₁ loaded in the tool 15 is shown in cross section in FIG. 11. At this point, substantially the full stripped end E₁ lies within the groove 98 and ready to be wrapped on the terminal t. In this position there is substantial friction holding the wire end E₁ in the groove 98 particularly in the area of the bend point 100 at the mouth of the closed groove 98. This friction may be sufficient to hold the sleeve 95 against rotation when only the lower pressure of the motor 52 is applied thereto. Thus, as the indexing arm 80 moves out of the range of the stop 81, the stripped end E₁ is loaded sufficiently to continue to hold the sleeve 95 in the illustrated position. In other instances, such as where the wire is of a very light gauge and thus very flexible and not tightly fitted in the groove 98, it may be desirable or necessary simply to terminate all rotary driving force to the sleeve 95 once the composite tool 15 starts its forward motion toward the terminal t. In any case, at the fully loaded position, the tool 15 is still spaced a distance from the end of the terminal t. The final Z axis movement is now provided by forward advancement of the entire main frame 11, and this final relative position (in the illustrated case, at the first Z level) is depicted by the dashed line outline of the terminal board B in FIG. 11. Subsequent one or two wrappings (second and third Z levels) on the same terminal may be effected if desired.

With reference now to FIG. 12, the advancing and retracting means 14 is shown in detail and the operation thereof will now be described. The main frame 11 includes a pair or rails 105, 106 that are supported in suitable roller bearings housed in four corner supports 107 thus forming a first sliding carriage of the advancing and retracting means 14. The corner supports 107 themselves make up a part of a mounting assembly, generally designated by the reference numeral 108. The mounting assembly 108 also includes an upstanding support 109 that carries the main operating cylinder 51, previously described. It will be recalled that this cylinder has its push rod connected to the sliding support 15a and thus the upstanding support 109 serves as a reaction point for the loading operation previously described.

The supports for the rails 105, 106 are substantially frictionless, and thus the main frame 11 is substantially freely movable with respect to the mounting assembly 108. On the other hand, the sliding support 15a

provides comparatively greater friction on its tracks and the friction of the sleeve 95 moving relative to the bit element 90 and the wire end is added thereto. Thus, it will be realized that if the mounting assembly 5 108 is free to move, the cylinder 51 would cause this movement in preference to the movement of the sliding support 15a. In order to prevent this from happening, the apparatus of the present invention provides a blocking latch or spacer cam means 110 10 that is pivotally mounted at the rear of the frame 11 and having an operative stop portion 111 engaging a shoulder on the mounting assembly 108. A trip means 112 having a yoke 113 holding the blocking latch 110 15 in sliding relationship is mounted on the sliding support 15a and is adapted to move forward when the same is pushed forward by the main cylinder 51.

Accordingly, with the stop portion 111 thus engaging the mounting assembly 108, the movement of the rails 105, 106 through the corner supports 107 is 20 prevented and the sliding support 15a will move forward. This thus allows the loading operation previously described to take place. As the sliding support 15a approaches the forward limit of its travel where the tool 15 is loaded (FIG. 11), the operative stop portion 111 is finally raised sufficiently by the latch means 110 so that the mounting assembly 108 is released and the forward motion of the main frame 11 is possible, as shown in FIG. 13 of the drawings. This thus allows the main frame to advance providing 25 the Z axis movement of the tool 15 to the terminal board B where the aperture 91 in the bit element 90 fully engages the aligned terminal t, as previously described with respect to the dotted line position of the board B of FIG. 11. For second and third Z level wrappings, the main frame 11 is merely stopped 30 short of full engagement of the aperture 91 on the terminal t by suitable stop means (not shown).

When a wrapping position is reached, the valve 62 40 is activated causing the shuttle valve 63 to switch modes (from either low or "off" conditions) and apply full power to the turbine motor 52. The sleeve 95 turns around the terminal t carrying with it the end E₁ trapped in the closed groove 98 and causing the wire to be wrapped around the terminal.

In the showing of FIG. 9, the insulation has been stripped starting below the tool 15 so that the wire W with insulation is positioned inside the groove 98. As the first wrap is made, it will thus be clear that at 50 least a portion of the insulated wire engages the terminal. This is known in the art as a modified wrap and has been shown in this application for illustrative purposes of the preferred embodiments. It should be understood that a regular wrap where only bare wire 55 engages the terminal t can be made by merely withdrawing the tool 15 momentarily so that the stripping blades can engage the wire at a point actually in line with the tool 15. As the successive wraps are made in both cases, it is important to maintain the proper 60 force on the tool to make each wrap in turn lie tightly against the previous wrap, yet not apply so great a force as to cause the successive wraps to pile up. This "backforce" varies with the gauge of wire employed and for the relatively light gauge wire 65 (thirty gauge, for example) now being most widely employed in the computer industry, a force of about one hundred grams should be used, and it is advan-

tageously regulated in the apparatus of the present invention by means that will now be described.

The bottom of the corner supports 107 are provided with additional openings and substantially frictionless bearings that receive additional guide rails 120, 121 mounted on the base assembly 45. These bearings provide an additional sliding interface which transforms the mounting assembly 108 into a second sliding carriage. A tension spring 122 representing the desired backforce is connected between one of the forward columns 107 and a stationary point on the base assembly 45. Thus, assuming the sliding support 15a has moved forward to load the wire and the operative stop portion 111 has been released so that the main frame 11 has moved to engagement with the terminal *t* and wrapping has commenced, the pressure of the tool face 96, 97 will be limited by the strength of the spring 122. This is so since the backward force is translated through the tool 15, the sliding support 15a, the upstanding support 109 and thence through the mounting assembly 108. The spring 122 may be selected to have substantially a constant tension force over a relatively broad range of movement so that the backforce is maintained substantially constant.

Furthermore, it will be noted that if a bent terminal post or pin is engaged during the advancing movement by the main frame 11, the pushing force will not exceed that of the spring 122 since once that threshold is reached, the spring 122 will give and the mounting assembly 108 will bodily move rearwardly to absorb any continuing movement in the main cylinder 51. In the event that a bent terminal is touched, the operator need only manually pull back the head 10 against the spring 122 to momentarily back the tool 15 away from the terminal, proceed to straighten the terminal so that it matches with the aperture 91 and then release the head 10 so that the tool 15 can resume the wrapping operation. In some cases, it is desirable to have a greater force, approximately 450 grams, acting as a backforce only as the tool is moved onto the terminal *t* in order to assure engagement and self-centering action if the tool 15 is only slightly off center with respect to the desired terminal *t*. Such an arrangement is provided for in the second embodiment and will be described below.

After the wrapping operation of the first end *E*, has thus been completed as described, the cylinders 38, 50, 51 are deactivated by the circuit 55 returning the parts to their home position. The feed tube 16 is already in the uppermost or home position and the wire *W* is thus extended through the front of the head 10 because of attachment of the wire to the first terminal *t*. When the uppermost position of the slide means 28 is reached due to deactivation of the cylinder 38, a pivotal holder 130 is pushed upwardly by an operating cam portion 131 to catch and further hold the wire, substantially as shown in FIG. 14. The X, Y locator 40 now moves the head 10 to the next position called for by the control logic 49.

Next, the feed tube 16 moves downwardly by reactivation of cylinder 22, as shown in FIG. 14, extending the potential second end *E*₂ of the wire through the open gripper jaws 18, 19, through the open door 25 of the cutting and stripping means and finally into engagement with the lower clamp 30. As the feed tube 16 moves down, the previous U-shaped loop now

cut free is knocked out and a new U-shaped control loop is ready to be formed when the feed tube 16 moves back, as shown in the first sequence drawing, FIG. 8. The gripper jaws 18, 19 are now closed and serve to positively position the wire *W* properly within the side loading notch 93 in readiness for forming said second end *E*₂. As will be realized, the door 25 is now closed and the slide means 28 is lowered to strip and cut the wire, and the operation of wrapping is repeated as set forth above.

In summary, it will be realized by those skilled in the art that a highly efficient wire handling and manipulating apparatus particularly adapted for wire wrapping of terminals has been provided in accordance with the teachings manifested in the illustration and description of the first embodiment of the present invention. The wrapping head 10 of said first embodiment features wire feeding means, catching and loading means 12 and cutting and stripping means 13 employing a minimum of structural components and a maximum of motion efficiency. The wire is positively controlled throughout by the feed tube 16, gripper jaws 18, 19 and the lower clamp 30. The wire *W* is firmly held in a notch 93 of a stationary bit element 90 and moved into a closed groove 98 by relative shifting movement of the sleeve 95. The sleeve only is then rotated to wrap the wire around the terminal *t*. The full movement and proper sequence of the loading operation and the advancing and retracting movement of the main frame 11 is assured by the blocking latch 110 and differential friction between the parts. An anti-backforce mechanism is built into a simple sliding interface and controlled by means of the spring 122.

Referring now to FIGS. 15-18, the structure which makes up the second embodiment of the present invention can be seen in detail. It will be recognized by those skilled in the art that the construction is such that the same basic function described above are also performed by the apparatus of the second embodiment. However, certain specific changes have been made in order to gain advantages not obtainable by utilizing other structure, such as shown in the first embodiment. As the description of this embodiment unfolds, it will be noted that several of the components and subcombinations are operated by separate actuators or motors, and this is basically a change to gain reliability of operation. Also, having the separate actuators assures even more positive control of the wire that is being manipulated so that this second embodiment is preferred in at least these two aspects. For ease of illustration and understanding, structure that is the same or equivalent to structure in the first embodiment will be designated by the same base reference numeral in a new 200-300 series. For those reference numerals that designate substantially different component parts, a 400 series of numerals is used. To further simplify the showing, the head 210 of the second embodiment is shown in the same upright orientation as the head 10 of the first embodiment, although it should be understood that insofar as operability is concerned, either head 10, 210 can be turned on its side or inverted if outside conditions, such as conflict with parts of the locator 44, dictate it.

With the above introduction, reference can now be made specifically to FIG. 15 wherein can be seen a

wire wrapping head, generally designated by the reference numeral 210, and comprising a main frame 211 having mounted thereon a wire catching and loading means, generally designated by the reference numeral 212. A stripping and cutting means 213 is positioned immediately below the catching and loading means, and down in the lower portion of the figure is shown the head advancing and retracting means 214. It should be noted again for emphasis, that the subcombinations 210-214 just described are basically like those of the first embodiment, but as will be seen more clearly below, the specific structure is different and the differences are significant in terms of improved reliability and assuring more positive control of the wire W.

The wire wrapping head 210 includes an elongated rotary wire wrapping tool 215 supported on sliding support 215a on slide rods with stop members 253 at the end thereof, as in the first embodiment. The drive motor 252 is mounted on the sliding support 215a and gears 270, 271 with the same indexing means as in the previous embodiment is utilized.

The wire W is fed into the system through a feed tube 216 (FIGS. 16-18) mounted on a pivotal block 220 and substantially identical to the corresponding part in the first embodiment. The wire is guided through the outlet orifice of the feed tube in cross engagement with the tool 215 and this can best be seen in FIGS. 17 and 18. As will be remembered from the previous discussion, the feed tube 216 is moved once during each wrapping cycle to the dotted line position (see FIG. 17) in order to feed a length of wire through the catching and loading means 212 and the stripping and cutting means 213 and thereby establish the first and second wire ends E₁, E₂ that are sequentially wrapped. As before, a cylinder 222 is operative to move the feed tube to accomplish this feeding operation. Stop means 290 and 291 are utilized at the opposite ends of the movement.

The feed tube 216 is in the second embodiment caught by an additional stop block 400 adjacent the outlet end of the tube. This gives the feed tube greater stability when the wire is held in the upper position just prior to the initiation of the wire end forming sequence. The opposite end of the feed tube is held captive in an elongated slot formed in guide plate 401. This guide plate is especially desirable to establish additional lateral stability where it is required to provide the feed tube 216 with a central offset portion, as shown in this embodiment, due to the necessity for space to position additional parts. Thus, as the feed tube 216 moves between the dotted line and the full line positions, the feed tube is restrained against lateral deviation from the path of feeding movement.

The stripping and cutting means 213 includes a pivotal door 225 with stripping blade 226 and cutting blade 227. Supporting the door 225 is combined backup member and slide means 228, which is adapted for up and down movement as shown in FIG. 17 along suitable guide rods.

Attached to the lower edge of the backup member 228 is a mounting block 405 having a pivotal cam element 406 positioned on pivot pin 407. This cam element is L-shaped and functions to trap the wire being fed downwardly by the feed tube 216 in a manner analogous to the corresponding cam element 30

in the previously described embodiment. The cam element 406 is designed to obtain greater efficiency of the trapping action but otherwise functions the same as in said first embodiment. As shown in FIG. 15A, a wider operative cam surface 408 is formed on the mounting block 405 and the wire W is capable of being clamped at any position along this surface 408. A return spring 409 is provided in order to constantly urge the cam element 406 into the clamping position. As the wire W is reversed and a new length of wire fed out, the U-shaped control loop is formed efficiently, as best shown in FIG. 15.

In addition to having a wider effective clamping face 408, the new design of the cam element 406 provides an angled side 410 forming a catch means without the necessity of having a laterally extending pin, as in the previous embodiment. Thus, as the wire is pulled upwardly during the feeding of each new wire end E₁, E₂ (note FIGS 8 and 14) and around the side 410, the cam element 406 is tended to be rotated in the counterclock-wise direction (FIG. 15) thus ensuring maintenance of a firm clamping action along surface 408 (FIG. 15A).

As can best be seen in FIGS. 16 and 17, the backup member and slide means 228 is constantly urged to the uppermost position by a suitable compression spring as before. However, the door 225 now is closed by a separate actuator cylinder 415. The downward movement of the slide means 228 is thus now performed by the single function cylinder 416 (FIG. 17). These cylinders are operated by any suitable control means for the machine so as to be properly in sequence. This is necessary to assure that the door is completely closed and the insulation on the wire scored, and the wire cut at a point below, prior to initiation of the downward movement of the slide means 228. The provision of two separate cylinders 415, 416 where before one was used gives improved reliability since the wire ends E₁, E₂ can be scored and cut before any tendency for downward movement is experienced. That is, by proper timing of the cylinder 416, there is no premature movement of the slide means 228 before the scoring and cutting has been performed. Also, with the separate cylinder 415 a more powerful interaction between the scoring blades 226 is gained and the cutting blade 227 engages its backup groove more firmly so that cleaner stripping and cutting is assured. It will of course be realized that where this operational aspect makes the second embodiment more desirable, for simplicity of the structure and when a sufficiently strong spring 39 (FIG. 34) is used, the corresponding subcombination of the first embodiment performs in an acceptable fashion.

For similar reliability and functional reasons, the sliding support 215a of the second embodiment has a separate actuator cylinder 420 connected between the rear main frame 211 and a bracket 421 mounted on the top of said sliding support 215a. This cylinder 420 now serves the sole function of shifting the outer sleeve 295 of the tool 215 forward during the loading operation of the formed wire ends E₁, E₂; whereas before, this function was performed by the main cylinder that also moved the head forward for wrapping. Additional cylinder 425 is provided in the second embodiment as a control means for moving said main frame 211 forward at the proper time.

In FIG. 15, the cylinder 425 is shown broken away in order to expose adjacent corner support 307 of the mounting assembly 308. The cylinder 425 is carried by the mounting assembly 308 by a suitable bracket 426 and piston rod 427 is attached to the rear main frame 211. As will be clear, after the cylinder 420 has been operated to cause loading of the tool 215, the cylinder 425 is separately actuated to move the main frame 211 forward to bring the loaded tool into the juxtaposition with the terminal to be wrapped.

Base assembly 245 supports the mounting assembly 308 by the guide rods 320 (not shown), 321 (see FIG. 15). Providing the additional cylinder 425 (in lieu of the latch mechanism of the first embodiment), assures more positive control since the exact moment of actuation and movement of the main frame 211 forward can be precisely selected to give the most favorable engagement with the terminal. Since the cylinder 425 is double acting, it can also serve to stop the advancement of the main frame 211 at any point, thereby giving the precise Z axis positioning of the wrapping head 210 required when the additional Z levels are to be wrapped.

In this embodiment, the wire catching and loading means 212 is also different from that disclosed in the previously described embodiment. This subcombination thus includes a gripping head 430 that is positioned just above and to one side of the bit element 290 of the tool 215 (see FIGS. 16, 17). This gripping head 430 is carried by an actuator cylinder 431, which is in turn stationarily mounted on the front main frame 211, as best shown in FIG. 16. On the opposite side of the wire W from the gripper head 430 is an anvil 432 against which the wire W is clamped by the gripping head 430. The anvil 432 is also stationarily mounted from the main frame 211, as is best shown in FIG. 15.

Thus, at the proper time in the sequence of operations, the gripping head 430 is moved by the cylinder 431 gripping the wire W against the stationary anvil 432. At this point, the door 225 has been closed and the slide means 228 is actuated in order to cut and strip the wire ends E₁, E₂. A more positive clamping action is attained since the direct force of the separate cylinder 431 bears against the wire W.

Since the gripper head 430 is withdrawn prior to the loading of the tool 215 and prior to moving the head 210 forward for wrapping, a separate pusher bar 435 is provided just above tool 215 (see FIG. 15) to guide and control the wire. The tip of the pusher bar 435 has a V-shaped face (FIG. 16) adapted to catch the wire just above the stripped end. The wire moves to the apex of the groove and is thereby kept from slipping off the side as the wire is moved to the terminal board to be wrapped. The end face is substantially in alignment with the end of the sleeve 295 of the tool 215 so that in the forwardmost position of the carriage 215a the wires W previously wound are tucked in between the terminals on the board. The apex of the V is laterally displaced slightly (to the left as seen in FIG. 16) so that the wire as it is approaching the terminals avoids conflict with terminals appearing on the board just above the terminal being wrapped. The features of positive gripping of the wire only at a stationary position with respect to the tool sleeve 295 that shifts for loading, releasing

the grip and then moving the wire forwardly assisted solely by the non-gripping pusher member 435 as the wire is loaded into the tool 215 results in less stress on the wire and greater flexibility for allowing the middle of the wire between the ends E₁, E₂ to nest cleanly between the terminals on the board.

After each wrapping of the first wire end E₁ around the selected terminal, the wire W is extending from the terminal through the front of the main frame 211 and into the outlet orifice of the feed tube 216. When the feed tube 216 then moves downwardly to feed a length of wire for the next wire end, that is, the second end E₂, it is important that the wire W be guided and held in the proper position to be received in the notch of the bit element 290. In this second embodiment, this holder means takes the form of a pin 440 extending transversely to the anvil 432 and positioned just above the gripping portion that cooperates with the gripper head 430. An actuator rod 441 (see FIGS. 16 and 18) is received in a loop in the opposite end of the pin 440, which rod is pivotally attached to a stationary point at pivot pin 442 on a bracket. A spring 443 biases the rod so as to move the holder pin 440 into the position crossing the path of the wire W.

As the stripping and cutting operation is being performed, the slide means 228 moves downwardly and a cam 444 thereon moves the rod 441 to the left, as seen in FIG. 18, to retract the holder pin 440 from the operative position. At all times that the slide means 228 is in the downward position, the pin is withdrawn thus allowing the wire W in front of the pusher 435 to move freely toward the terminal board for the wrapping operation (see FIG. 18). With the holder pin 440, a position closer to the exact location of the wire W within the notch of the bit element 290 can be obtained, and thus more positive and efficient control of the wire W is accomplished.

As previously set forth in the description of the first embodiment, a resilient anti-backforce should be applied to the head 211. As the tool 215 moves forward, if a bent terminal is engaged, it is desirable that the terminal not be bent further out of place but instead the head 211 be resiliently stopped whereupon the operator can realign the tool and release the head for the immediate continuation of the wrapping operation. For this purpose, in the second embodiment, a biasing means or spring 450 is mounted on piston rod 451 of an operator cylinder 452. The free end of the spring abuts, but is not attached to a bracket 453 fixed on the carriage or mounting assembly 308. Thus, assuming the main frame 211 advanced by the cylinder 425 to the terminal board, any backward force or resistance on the carriage 308 is resisted and absorbed by the spring 450. Normally, the spring 450 is in this position as the head 211 is being advanced so that the bit element 290 will cleanly receive and provide the necessary forward force to move onto the terminal that is to be wrapped. The force normally desirable for this function of the anti-backforce mechanism is approximately 450 grams.

Once the bit element 290 is properly positioned on the terminal (see FIG. 11), the anti-backforce needed to assure proper winding of the wire W has been found to be considerably less than 450 grams when the relatively light gauge wire as contemplated here is being used. Thus, in this case, just as the sleeve 295 of the tool 15 starts to rotate the piston rod 451 is

retracted to withdraw the spring 450 from operative engagement with the bracket 453. When this is done, the friction of the supporting rods 320, 321 in the corner supports 307 is relied upon to provide the approximately one hundred grams of force that is needed to assure a tightly wound coil without overlapping. Thus, with this embodiment, the strength of the backforce can be selected to best suit the exact operation being performed at the time.

In summary, two embodiments of a wire wrapping apparatus have been shown and described. In both embodiments, the same basic functions are performed to obtain highly efficient winding of wire on the terminals by avoiding the prior art shortcomings described above. The wire W is gripped prior to the stripping and cutting operation so that positive control is maintained and a U-shaped control loop is formed in order to further provide for positive control. In the second embodiment, the wire adjacent the prepared end is guided and moved to the terminal board by a separate pusher bar. A holding pin 440 is projected into the path of the wire in order to assure that the wire is positioned in the notch of the bit element 290 on the tool 215 after the first wrap. Also, in the second embodiment, the anti-backforce mechanism includes a means for retracting the spring 450 from operative engagement whereby the anti-backforce for wrapping may depend on a relatively lighter force.

In this disclosure, there is shown and described the two preferred embodiments of the invention, but, as aforementioned, it is to be understood that the invention is capable of use in various other combinations and environment and is capable of changes or modifications within the scope of the inventive concept as expressed herein.

1. A wire wrapping apparatus for interconnecting electrical terminals comprising a rotary wire wrapping tool, means for feeding wire of an indeterminate length to said tool, means for catching and loading said wire on said tool including gripper means separate from but adjacent said tool, stripping and cutting means for forming the first and second connector ends of said wire to be wrapped on the terminals, said gripper means positively holding said wire at least during stripping, means for relatively advancing and retracting at least said tool with respect to said terminal, said advancement being along the Z axis of the tool and toward said terminal, means for rotating said tool to perform the wrapping operation, and locator means for relatively traversing said tool with respect to said terminals to a new X, Y location, whereby a single tool with minimal frontal area is operative to position and wrap both ends at the proper Z level on said terminals to form a complete wired interconnection.

2. The wire wrapping apparatus of claim 1 wherein the operative portion of said gripper means is substantially fixed in position relative to said tool and aligned with said stripping and cutting means to hold said wire against the pulling force of the stripping operation and in position for loading.

3. The wire wrapping apparatus of claim 1 wherein said shifting means is operative to load said wire ends only after the same have been cut and stripped, whereby fracture of said wire due to excessive tension is avoided.

4. The wire wrapping apparatus of claim 1 wherein said gripper means is mounted for relative movement with said sleeve to maintain the positive holding condition while the wire is being loaded.

5. The wire wrapping apparatus of claim 1 wherein said gripper means is mounted separate from said shifting means and is released prior to the wire being loaded, and pusher means to intercept the wire adjacent the stripped end to move the same to said terminals.

10 6. The wire wrapping apparatus of claim 1 wherein is further provided clamp means adjacent said cutting means to positively control the end of said wire presented thereto prior to the cutting thereof.

15 7. The wire wrapping apparatus of claim 6 wherein said clamp means includes a cam element and opposed jaw to form a nip to trap the wire, said cam element being pivoted so as to open to receive the wire as the same is pulled in a first direction, and biasing means to 20 urge said cam element against said jaw.

25 8. The wire wrapping apparatus of claim 7 wherein said clamp means includes a catch means on the side of said cam element to receive said wire when pulled in the opposite and second direction for forming a U-shaped control loop and increasing the clamping action.

30 9. The wire wrapping apparatus of claim 8 wherein said catch means includes the side of said cam element to be engaged by said loop and a laterally extending pin on said side to form a V-shaped notch for gripping said loop.

35 10. The wire wrapping apparatus of claim 1 wherein said gripper means includes a stationary jaw and a movable jaw extending substantially parallel to and aligned with said tool and on the side opposite said stripping and cutting means, means for supporting said movable jaw and means for actuating said movable jaw.

40 11. The wire wrapping apparatus of claim 10 wherein said actuating means comprises a fluid cylinder mounted stationary relative to said tool, said movable jaw being mounted on the piston rod of said cylinder for direct action.

45 12. The wire wrapping apparatus of claim 1 wherein is further provided holder means on said apparatus separate from said tool and said gripper means for positively capturing said wire as positioned by said feeding means, said holder means being movably mounted adjacent said gripper means and operative to hold said wire for gripping by said gripper means when the new X, Y location is reached and before the cutting and stripping operation.

50 13. The wire wrapping apparatus of claim 12 wherein said holder means comprises a pin extending transversely of said gripper means and adjacent thereto, said pin being on the side of said gripper means opposite said stripping and cutting means, and actuator means to retract said pin from the capturing position to allow the tool to move relatively along the Z axis to said terminal.

55 14. The wire wrapping apparatus of claim 12 wherein said stripping and cutting means includes a movable member and backup member assembly adjacent said tool, at least one stripping blade adjacent said tool and at least one cutter blade spaced therefrom on said assembly, movable mounting means

for said assembly and means for moving said assembly toward the end of said wire formed by the cutter to strip the insulation in readiness for wrapping, a cam on said slide means operative to actuate said holder means on the return stroke of said movable mounting means.

15. A wire wrapping apparatus for interconnecting electrical terminals comprising a rotary wire wrapping tool, means for feeding wire of an indeterminate length to said tool, means for catching and loading said wire on said tool including gripper means adjacent said tool positively holding said wire, said wrapping tool comprising an elongated bit element, a transversely extending open notch on one side of said bit element adjacent said gripper means, an aperture in the end of said bit element for receiving the terminal, an elongated sleeve on said bit element, a longitudinally extending slot formed in said tool and separated by at least a portion of said bit element to form an open groove and a closed groove contiguous with said portion of said bit element, and means for relatively shifting said sleeve and said bit element to load said wire into said closed groove through said open groove and notch, stripping and cutting means for forming the first and second connector ends of said wire to be wrapped on the terminals, means for relatively advancing and retracting at least said tool with respect to said terminal, said advancement being along the Z axis of the tool and toward said terminal, means for rotating said tool to perform the wrapping operation, and locator means for relatively traversing said tool with respect to said terminals to a new X, Y location, whereby a single tool with minimal frontal area is operative to position and wrap both ends at the proper Z level on said terminals to form a complete wired interconnection.

16. The wire wrapping apparatus of claim 15 wherein said feeding means includes a feed tube carrying said wire therein and mounted substantially normal to said tool, means for bodily shifting said feed tube prior to each wrapping cycle to feed and position said wire in operative relationship with said gripper means and said stripping and cutting means, and the outlet end of said feed tube is aligned with said notch, said gripper means serving to catch said wire and position the same in said notch for loading on said tool.

17. The wire wrapping apparatus of claim 16 wherein said feed tube is mounted for pivotal action about an axis substantially normal to the path of shifting movement to allow glancing action past said gripper means and said clamp, and stop means adjacent the ends of the path of travel of said feed tube to engage the wire inlet end to pivot said tube and thereby extend the stroke of the wire outlet end and positively hold said tube and the wire in position.

18. A wire wrapping apparatus for interconnecting electrical terminals comprising a rotary wire wrapping tool, means for feeding wire of an indeterminate length to said tool, means for catching and loading said wire on said tool including gripper means adjacent said tool positively holding said wire, stripping and cutting means for forming the first and second connector ends of said wire to be wrapped on the terminals, said stripping and cutting means including a movable member and backup member assembly adjacent said tool, said wire passing between said members, at least one stripping blade adjacent said tool and at

least one cutter blade spaced therefrom on said assembly, movable mounting means for said assembly, means for closing said movable member against said backup member, and means for moving said assembly toward the end of said wire formed by the cutter to strip the insulation in readiness for wrapping.

19. The wire wrapping apparatus of claim 18 wherein is provided clamp means adjacent said cutting means to positively control the end of said wire presented thereto prior to the cutting thereof, said clamp means being mounted on the backup member of said assembly.

20. The wire wrapping apparatus of claim 18 wherein is provided a motor means for sequentially actuating said movable member and moving said assembly, whereby to assure capture by said movable member of said wire for successful stripping and cutting action.

21. The wire wrapping apparatus of claim 20 wherein said motor means includes a fluid cylinder, an operating cam mounted on said assembly and engaging said movable member, the piston rod of said cylinder being operative to actuate said movable member and only thereafter move said slide means.

22. A wire wrapping apparatus for interconnecting electrical terminals comprising a rotary wire wrapping tool, means for feeding wire of an indeterminate length to said tool, means for catching and loading said wire on said tool including gripper means adjacent said tool positively holding said wire, stripping and cutting means for forming the first and second connector ends of said wire to be wrapped on the terminals, means for relatively advancing and retracting at least said tool with respect to said terminal, said advancement being along the Z axis of the tool and toward said terminal, means for rotating said tool to perform the wrapping operation, and locator means for relatively traversing said tool with respect to said terminals to a new X, Y location, said loading means for said tool being mounted on a sliding support, a first motor means operating said loading means, a main frame for mounting the above-mentioned parts, a second motor means connected to said main frame, a mounting assembly for said second motor to provide a reaction point, said main frame being movably mounted on said mounting assembly and forming a first sliding carriage, said second motor means being operative to advance said main frame, to bring said tool into engagement with said terminal, said mounting assembly being movably mounted on a base member and forming a second sliding carriage, and biasing means connected between said mounting assembly and said base member, said biasing means limiting the backforce on said tool as the wire is wrapped on said terminal and limiting the forward force of said tool to prevent bending of a misaligned terminal, whereby a single tool with minimal frontal area is operative to position and wrap both ends at the proper Z level on said terminals to form a complete wired interconnection.

23. The wire wrapping apparatus of claim 22 wherein said gripper means forming a part of said catching means is mounted on said main frame apart from said sliding support.

24. The wire wrapping apparatus of claim 22 wherein said second motor means operates as a control means to hold said main frame with respect to said sliding support.

25. The wire wrapping of claim 24 wherein said second motor means comprises a fluid cylinder to be operated sequentially with said first motor means for said sliding support.

26. The wire wrapping apparatus of claim 22 wherein said first motor means and said second motor means includes a fluid cylinder, the friction of said sliding support being greater than that of said main frame to allow full retraction of the latter prior to retracting movement of said sliding support by said fluid cylinder.

27. The wire wrapping apparatus of claim 26 wherein is provided a control means to hold said main frame including a latch means comprising a spacer cam member positioned in blocking relationship between said main frame and said first carriage to prevent relative movement therebetween, and means mounted on said sliding support operative to trip said spacer member from the blocking position.

28. The wire wrapping apparatus of claim 22 wherein is provided third motor means connected to said biasing means to vary the operative force therein, whereby one force for forward moving of the tool on the terminal and another lighter force for forming the backforce is employed.

29. A wire wrapping apparatus for interconnecting electrical terminals comprising a rotary wire wrapping tool, means for feeding wire of an indeterminate length to said tool, means for catching and loading said wire on said tool including gripper means adjacent said tool positively holding said wire, stripping and cutting means for forming the first and second connector ends of said wire to be wrapped on the terminals, means for rotating said tool to perform the wrapping operation, said means for rotating said tool comprising an air turbine motor, air supply means, an indexing arm mounted for rotation with said motor, and stop means on said apparatus positioned in the path of said arm when said tool is retracted, whereby said tool is indexed for loading while rotating in the same direction as during driving.

30. The wire wrapping apparatus of claim 29 wherein said air supply means includes high and low pressure feeding means for interconnection during the wire wrapping and the indexing operations, respectively.

31. An apparatus for preparing and connecting a stripped wire end to an electrical terminal comprising a tool for affixing the end to the terminal, means for feeding wire of an indeterminate length to said tool, means for catching and loading said wire on said tool including gripper means adjacent said tool positively holding said wire, stripping and cutting means for forming the wire end, means for relatively advancing and retracting said tool with respect to said terminal, said advancement being along the Z axis of the tool and toward said terminal, means to affix said wire end to said terminal, said stripping and cutting means including a movable member and backup member assembly adjacent said tool, said wire passing between said members, at least one stripping blade adjacent said tool and at least one cutter blade spaced therefrom on said assembly, movable support means for said assembly, means for closing said movable member against said backup member and means for moving said assembly toward the end of said wire formed

by the cutter to strip the insulation in readiness for connecting by said affixing means.

32. The preparing and connecting apparatus of claim 31 wherein is provided first motor means for sequentially actuating said movable member and moving said movable support means, whereby to assure capture of said wire for successful stripping and cutting action.

33. The preparing and connecting apparatus of claim 32 wherein said first motor means includes a fluid cylinder for actuating said movable member and a separate fluid cylinder for moving said movable support means.

34. The preparing and connecting apparatus of claim 32 wherein is provided second motor means for sequentially actuating said gripper means before stripping and cutting and third motor means for loading and advancing said tool after said stripping and cutting.

35. The preparing and connecting apparatus of claim 34 wherein said third motor means includes a fluid cylinder for effecting loading the tool and a separate fluid cylinder for relatively advancing the tool with respect to the terminal.

36. A wire wrapping tool assembly for interconnecting a wire to electrical terminals comprising a rotary wire wrapping tool, means for catching and loading said wire on said tool including gripper means separate from but adjacent said tool, stripping and cutting means for forming the first and second connector ends of said wire to be wrapped on the terminals, said gripper means positively holding said wire during stripping, means for relatively advancing and retracting at least said tool with respect to said terminal, said advancement being along the Z axis of the tool and toward said terminal, and means for rotating said tool to perform the wrapping operation, whereby a single tool with minimal frontal area is operative to position and wrap the end at the proper Z level on said terminal to form a connection.

37. The wire wrapping tool assembly of claim 36 wherein is further provided clamp means adjacent said cutting means to positively control the end of said wire presented thereto prior to the cutting thereof.

38. The wire wrapping tool assembly of claim 37 wherein said clamp means includes a cam element and opposed jaw to form a nip to trap the wire, said cam element being pivoted so as to open to receive the wire as the same is pulled in a first direction, and biasing means to urge said cam element against said jaw.

39. The wire wrapping tool assembly of claim 36 wherein is further provided feeding means including a feed tube carrying said wire therein and mounted substantially normal to said tool, means for bodily shifting said feed tube prior to each wrapping cycle to feed and position said wire in operative relationship with said gripper means and said stripping and cutting means.

40. A wire wrapping tool assembly for connecting a wire to a terminal comprising a rotary wire wrapping tool, said wrapping tool comprising an elongated bit element, a transversely extending open notch on one side of said bit element adjacent said gripper means, an aperture in the end of said bit element for receiving the terminal, an elongated sleeve on said bit element, a

longitudinally extending slot formed in said tool and separated by at least a portion of said bit element to form an open groove and a closed groove contiguous with said portion of said bit element, and means for relatively shifting said sleeve and said bit element to load said wire into said closed groove through said open groove and notch, means for catching and loading said wire on said tool including gripper means adjacent said tool positively holding said wire, stripping and cutting means for forming the connector end of said wire to be wrapped on the terminal, means for relatively advancing and retracting at least said tool with respect to said terminal, said advancement being along the Z axis of the tool and toward said terminal, and means for rotating said tool to perform the wrapping operation, whereby a single tool with minimal frontal area is operative to position and wrap the end at the proper Z level on said terminal to form a connection.

41. The wire wrapping tool assembly of claim 40 wherein the operative portion of said gripper means prior to advancement is aligned with said stripping and cutting means and said notch to hold said wire against the pulling force of the stripping operation and in position for loading.

42. The wire wrapping tool assembly of claim 40 wherein said shifting means is operative to load said wire end only after the same has been cut and stripped, whereby fracture of said wire due to excessive tension is avoided.

43. The wire wrapping tool assembly of claim 40 wherein is provided a pusher means mounted for movement by said shifting means with said sleeve to maintain a positive holding condition while the wire is being loaded and during advancement to the terminal.

44. The wire wrapping tool assembly of claim 40 wherein said gripper means includes two relatively movable jaws extending substantially parallel to and aligned with said tool, said gripper means being on the side of said tool opposite said stripping and cutting means, said gripper means being mounted separate from said shifting means.

45. A wire wrapping tool assembly for connecting

a wire to a terminal comprising a rotary wire wrapping tool, means for catching and loading said wire on said tool including gripper means adjacent said tool positively holding said wire, stripping and cutting means for forming the connector end of said wire to be wrapped on the terminal, said stripping and cutting means including a movable member and backup member assembly adjacent said tool, at least one stripping blade adjacent said tool and at least one cutter blade spaced therefrom on said assembly, said wire passing between said members, movable mounting means for said assembly, means for closing said movable member against said backup member, and means for moving said assembly toward the end of said wire formed by the cutter to strip the insulation in readiness for wrapping, means for relatively advancing and retracting at least said tool with respect to said terminal, said advancement being along the Z axis of the tool and toward said terminal, and means for rotating said tool to perform the wrapping operation, whereby a single tool with minimal frontal area is operative to position and wrap the end at the proper Z level on said terminal to form a connection.

46. A wire wrapping tool assembly for interconnecting a wire to electrical terminals comprising a rotary wire wrapping tool, means for catching and loading said wire on said tool including gripper means separate from but adjacent said tool, stripping and cutting means for forming the first and second connector ends of said wire to be wrapped on the terminals, said gripper means positively holding said wire during stripping and means for rotating said tool to perform the wrapping operation, whereby a single tool with minimal frontal area is operative to position and wrap the end on said terminal to form a connection.

47. The wire wrapping tool assembly of claim 46 wherein is further provided clamp means adjacent said cutting means to positively control the end of said wire presented thereto prior to the cutting thereof, the connector end of the wire thereby being positively controlled adjacent said tool and adjacent said cutting means.
